(57) **CLAIM**

The ornamental design for an electronic taper candle having a flame-shaped element illuminated on two sides thereof, as shown and described.

DESCRIPTION

FIG. 1 is an isometric view of the electronic taper candle; FIG. 2 is a front view of the electronic taper candle of FIG. 1, illustrating the illuminated area on one side of the flame-shaped element;

FIG. 3 is a rear view of the electronic taper candle of FIG. 1, illustrating the illuminated area on the opposite side of the flame-shaped element;

FIG. 4 is a left side view of the electronic taper candle of FIG. 1;

FIG. 5 is a right side view of the electronic taper candle of FIG. 1;

FIG. 6 is a top view of the electronic taper candle of FIG. 1; and,

FIG. 7 is a bottom view of the electronic taper candle of FIG. 1.

The broken lines of FIGS. 1-7 are provided for purposes of illustration and form no part of the claimed design of the present application. However, the broken lines are intended to provide explicit disclosure as to presently unclaimed portions of the design, and Applicants reserve the right to pursue and claim such other presently unclaimed portions in one or more continuation applications.

1 Claim, 4 Drawing Sheets
